United States Patent Office.

JOSEPH RECKENDORFER AND TEILE H. MÜLLER, OF NEW YORK, N. Y.,
ASSIGNORS TO JOSEPH RECKENDORFER.

Design No. 4,642, dated February 7, 1871.

DESIGN FOR A LEAD-PENCIL.

The Schedule referred to in these Letters Patent and making part of the same.

To whom it may concern:

Be it known that we, JOSEPH RECKENDORFER and TEILE H. MÜLLER, of the city, county, and State of New York, have invented a new and original Design for Lead-Pencils, of which the following is a specification.

Our design, as illustrated in the accompanying drawing, consists of a lead-pencil, the wooden part of which is made with a swell or enlarged part, *a*, in the center or about midway between the two ends, and thence gradually tapering or decreasing in diameter toward the ends, as shown at *b*.

The stamp, indicating the quality or name of the pencil, is to be placed on the middle part *a*, thus leaving the ends free to be cut.

This pencil possesses several advantages over the ordinary wooden pencil, which has the same diameter throughout its length—

First, when held for writing or drawing it adapts

itself more readily to the hand, permits an easier, firmer hold, and can be held with a nicer balance.

Second, it can be made from wood that is somewhat imperfect or otherwise too small throughout its length to produce an ordinary round pencil.

Third, the stamp is placed in the center or middle, so that both ends are left free to be sharpened, and the ends, being small, can be more easily and quickly sharpened than those of an ordinary pencil.

What we claim, and desire to secure by Letters Patent, is—

The design for lead-pencils, as herein shown and described.

In testimony whereof we have hereunto set our hands in the presence of two subscribing witnesses.

JOS. RECKENDORFER.
